GEORGE F. SHAVER, OF NEW YORK, N. Y., ASSIGNOR TO THE HYDRAGAS CORPORATION, A CORPORATION OF NEW YORK.

METHOD OF INCREASING THE POWER OF GAS-ENGINES.

1,343,938.

Specification of Letters Patent. Patented June 22, 1920.

Application filed November 9, 1916, Serial No. 130,327. Renewed August 13, 1919. Serial No. 317,348.

To all whom it may concern:

Be it known that I, GEORGE F. SHAVER, a citizen of the United States, and resident of the city, county, and State of New York, have invented certain new and useful Improvements in Methods of Increasing the Power of Gas-Engines, of which the following is a specification.

This invention relates to a system or method for increasing the power and efficiency of a gasolene engine, having for an object both to effect a more complete combustion of the fuel in the engine cylinders and also to render possible the use of an additional element which in combination with the carbon forms an explosive gas, thereby increasing the power without increasing the fuel consumption, a further object being to keep the cylinder walls free from carbon deposits.

To accomplish this result I cause to be introduced into the explosion chamber a mixture of explosive gases and an additional gas, preferably an oxidizing gas to remove the carbon, making use of the heat of reaction from the explosion to render the gases more active. I also contemplate making use of water vapor and moist gases having oxidizing properties.

In the accompanying drawing I have illustrated one manner in which my invention may be applied in connection with a four cylinder gas engine. The details of construction of the engine have not been shown but merely indicated, as these are well known and it will be obvious that the system or method is adapted for use with various engine constructions.

The engine cylinders are indicated at 1, 2, 3 and 4 and are provided with the usual intake manifold 5.

The radiator is indicated at 6, and is provided with the usual overflow pipe 7.

The construction and arrangement of the overflow pipe in the radiator is well known and consists of a pipe that is open at both ends, the upper end extending slightly above the normal level of the water in the radiator and providing an outlet for the water vapors and an overflow when water reaches a given height. As here shown, a small pipe 8 is attached to the manifold 5 at one end and to the overflow pipe 7 in the radiator 6 near the upper end thereof.

It may also be desirable to provide a

turn, shown at 9, in the tube 8 to form a trap preventing any water from flowing through the tube 8 to the manifold 5. A valve 10 may also be provided in the tube 8 to shut off the device when desired.

In the present instance, to produce the oxidizing gas I add to the water in the radiator a compound which will readily give off oxygen, such, for instance, as peroxid of hydrogen, which is a colorless liquid composed of two parts of hydrogen and two parts of oxygen chemically combined and having the formula H_2O_2 . Under the action of heat the peroxid of hydrogen decomposes into water and oxygen.

Referring now to the drawings, it will be seen that when the engine is running and the water in the radiator is warm, water vapors and gases from the peroxid of hydrogen will collect in the upper part of the radiator and be drawn therefrom through the overflow pipe 7 and tube 8 to the manifold 5, where they become mixed with the gasolene fuel vapors or gases and are drawn into the explosion chambers of the cylinders. The moisture and heat assist in the chemical action in which the carbon in the cylinder is combined with the oxygen to form carbon monoxid, which is an explosive gas, while the intense heat of the explosion and pressure tend to liberate hydrogen from the water vapor, which being also explosive, thus furnishes an additional explosive gas in the explosion chamber.

It is understood that the engine is also being operated by the explosion of gasolene vapor and air while the above reactions are taking place and these explosions cause intense heat and accelerate the reactions and that the carbon monoxid and hydrogen gas, mixed with the gasolene vapor and air, explode simultaneously therewith and thus add power to the explosion. The presence of moisture also assists in the reactions, above explained.

It will thus be seen that not only is a more powerful explosion produced by the use of this system but that the carbon deposits in the cylinder are removed and prevented from accumulating, which materially adds to the efficiency of the engine.

Any tendency of the peroxid of hydrogen to attack and oxidize the metal parts of the radiator and pipes can be readily overcome by nickelizing or leading the exposed parts,

although in actual practice the percentage of the peroxid is so small and the vapors are drawn off and used so quickly that no injurious action takes place.

5 At high speeds or when the throttle is opened wide an additional supply of air is obtained from the lower end of the overflow tube 7.

What I claim is:—

- 10 1. The method for increasing the power of gas engines which consists in heating a relatively large amount of water and a relatively small amount of an additional substance adapted to give off an oxidizing gas, and introducing said gas and water vapor thus formed into the explosion chamber of the engine.
- 15 2. The method for increasing the power of gas engines which consists in mixing with water a compound having a larger percentage of oxygen than that of water; heating such mixture, and introducing the gas and vapor thus formed into the explosion chamber of the engine.
- 20 3. The method for increasing the power

of gas engines which consists in heating a solution containing a relatively large amount of water and a relatively small amount of a substance adapted to give off an oxidizing gas, and introducing said gas 30 and water vapor thus formed into the explosion chamber of the engine.

4. The method for increasing the power of gas engines which consists in heating a solution of a relatively large amount of water and a relatively small amount of peroxid of hydrogen and introducing the gas and vapor thus formed into the explosion chamber of the engine.

5. The method for increasing the power 40 of gas engines, which consists in heating a solution of water and peroxid of hydrogen to cause a vapor to be given off and introducing such vapor into the explosion chamber of an internal combustion engine of the 45 hydrocarbon type.

Signed at the city, county and State of New York, this 8th day of November, 1916.

GEORGE F. SHAVER.
